UNITED STATES PATENT OFFICE

108,231

DESIGN FOR AN AIR CIRCULATING HEATING STOVE

Edwin Esson, Kalamazoo, Mich., assignor to
Kalamazoo Stove Company, Kalamazoo, Mich.,
a corporation of Michigan

Application December 1, 1937, Serial No. 73,290

Term of patent 3½ years

To all whom it may concern:

Be it known that I, Edwin Esson, a citizen of the United States, residing at Kalamazoo, in the county of Kalamazoo and State of Michigan, have invented a new, original, and ornamental Design for Air Circulating Heating Stove, of which the following is a specification, reference being had to the accompanying drawing, forming a part thereof, in which:

Fig. 1 is a front elevation,
Fig. 2 is a side elevation, and
Fig. 3 is a plan view of an air circulating heating stove, showing my new design.

I claim:
The ornamental design for an air circulating heating stove, as shown. EDWIN ESSON.
